UNITED STATES PATENT OFFICE.

ALFRED MILLER, OF TORONTO, ONTARIO, CANADA.

SANITARY PROTECTOR FOR HEAD-RESTS FOR BARBERS' CHAIRS.

No. 838,733.

Specification of Letters Patent.

Patented Dec. 18, 1906.

Application filed June 8, 1906. Serial No. 320,852.

To all whom it may concern:

Be it known that I, ALFRED MILLER, of the city of Toronto, in the county of York, in the Province of Ontario, Canada, have invented certain new and useful Improvements 5 in Sanitary Protectors for Head-Rests for Barbers' Chairs, of which the following is a specification.

My invention relates to improvements in 10 sanitary head-rests for barbers' chairs; and the object of the invention is to devise a simple means whereby the head-rest may be preserved in a sanitary condition and the use of towels thereon dispensed with and at the 15 same time provide paper to receive the lather from the razor.

Further objects are to make the device 20 capable of being operated and utilized by the barber behind the chair, and thus obviate interfering with the comfort of the customer or occupant of the chair.

In the accompanying drawings, Figure 1 is 25 a perspective view of a head-rest provided with my improvement. Fig. 2 is a transverse section.

In the drawings like characters of reference indicate corresponding parts in each figure.

A is the cushion of the head-rest, which is 30 supported on a base A', located at the top of the stem B.

2 represents bearings extending forwardly from the ends of the base of the head-rest, in which is carried the roller A³.

35 A² represents rearwardly-extending lugs attached to the head-rest, and 3 represents hangers from which the cylinder C is supported, such hangers being suitably fastened to the ends of the cylinder.

40 C' is a knife or cutting-bar secured to the cylinder, and C² is the longitudinal arc-shaped flap, which is hinged at C² to the main body of the cylinder and extends to the slot 4 at the top, being held closed by any 45 suitable spring or other means.

E is the roller on which the paper D is carried. The paper passes outwardly through the slot 4 over the top of the head-rest, then under the roller A³, and backwardly again underneath the top layer, thence downwardly in front of the hangers A² and cylinder C.

The position shown in the drawings is that in which the cylinder C ordinarily hangs when at rest.

55 In order to enable the paper to be cut and a clean portion of the paper to be substituted

at the top after a customer has left the chair and ready for another customer, I pull upon the paper D, thereby throwing it and the roller C into the position shown in dotted 60 lines in Fig. 2, in which position the paper may be readily drawn outwardly until sufficient has been taken away to leave a clean portion at the top of the head-rest.

By pressing slightly upon the roller and 65 giving a lateral pressure to the paper where the knife-bar contacts with the same I am enabled to sever the paper on the line of the knife-bar. This severed paper may be utilized to receive the lather from the razor 70 when shaving a customer.

I am aware that it is not broadly new to provide a paper cover for the top of the head-rest nor to have a cylinder in which the paper is located, and I do not claim the use of the cylinder and paper, broadly. In my invention, however, the paper is carried in a roller behind the head-rest and is manipulated from behind the chair without interfering with the comfort of the customer, which is an important desideratum. 75

What I claim as my invention is—

1. The combination with the head-rest, of a roller located in front of the head-rest, a cylinder hung from the rear of the head-rest 85 and carrying a roll of paper, the paper from which extends through a slot in the cylinder up over the head-rest around the front roller and backwardly again underneath the upper layer of paper and down in front of the cylinder as and for the purpose specified.

2. The combination with the head-rest, of a roller located in front of the head-rest, a cylinder hung from the rear of the head-rest and carrying a roll of paper, the paper from 95 which extends through a slot in the cylinder up over the head-rest around the front roller and backwardly again underneath the upper layer of paper and down in front of the cylinder, and a knife-bar carried by the cylinder as and for the purpose specified.

3. The combination with the head-rest, of a roller located in front of the head-rest, a paper-carrying means located to the rear of the head-rest, the paper of which extends up 105 over the head-rest around the front roller and backwardly again underneath the upper layer of paper and down in front of the paper-carrying means as and for the purpose specified.

4. The combination with the head-rest, of a roller located in front of the head-rest, a

paper-carrying means located to the rear of the head-rest, the paper of which extends up over the head-rest around the front roller and backwardly again in front of the paper-carrying means, and means located behind the head-rest for severing the paper as and for the purpose specified.

5. The combination with the head-rest, of a roller located in front of the head-rest and a 10 roller hung from the rear of the head-rest and

carrying the roll of paper, the paper from which extends over the head-rest around the front roller and backwardly again underneath the upper layer of paper and downwardly in front of the rear roller as and for 15 the purpose specified.

ALFRED MILLER.
